US00D886638S

(12) **United States Design Patent** (10) **Patent No.:** **US D886,638 S**
Bhalla et al. (45) **Date of Patent:** **** Jun. 9, 2020**

(54) **PACKAGING**

(71) Applicant: **JUUL Labs, Inc.**, San Francisco, CA (US)
(72) Inventors: **Rajeev Bhalla**, Palo Alto, CA (US); **Jason Curtis**, San Francisco, CA (US); **Peter C. De Alva**, Lake Zurich, IL (US); **PyiPhyo Lwin**, Newark, CA (US); **James Monsees**, San Francisco, CA (US); **Kevin J. Myers**, San Jose, CA (US); **Vincent C. Phua**, Piedmont, CA (US); **Jambunathan Vangal Ramamurthy**, San Jose, CA (US); **Alexandra N. Siano**, San Francisco, CA (US); **Srinivasan Sundararajan**, Cupertino, CA (US); **Bryan White**, San Francisco, CA (US); **Thomas J. White**, San Francisco, CA (US)

(73) Assignee: **JUUL Labs, Inc.**, San Francisco, CA (US)

(**) Term: **15 Years**

(21) Appl. No.: **29/659,407**

(22) Filed: **Aug. 8, 2018**

(51) LOC (12) Cl. **09-03**

(52) U.S. Cl.

USPC **D9/737; D9/759; D9/732**

(58) **Field of Classification Search**

USPC D9/414-423, 424-429, 430-433, 434, D9/456, 457, 711, 713, 721-722, 732, D9/737, 759; D3/272-274, 290, 304, D3/305, 310, 311, 312, 313, 314, 315, D3/319; D20/10, 22, 27, 40, 42

CPC ... B65D 5/00; B65D 5/02; B65D 5/18; B65D 5/20

(57) **CLAIM**

The ornamental design for a packaging, as shown and described.

DESCRIPTION

FIG. 1 is a bottom, front, and right side perspective view of a packaging of our design;

FIG. 2 is a bottom, front, and left side perspective view thereof;

FIG. 3 is a front view thereof;

FIG. 4 is a rear view thereof;

FIG. 5 is a right side view thereof;

FIG. 6 is a left side view thereof;

FIG. 7 is a bottom view thereof; and,

FIG. 8 is a top view thereof.

The long dash-dot broken lines illustrate perforations that form a part of the claimed design.

1 Claim, 6 Drawing Sheets
